SUPPORT FOR COAT HANGERS

John O. Rosene, Sioux City, Iowa

Application August 9, 1956, Serial No. 42,555

Term of patent 14 years

(Cl. D80—8)

Figure 1 is a front elevational view of a support for coat hangers, showing my new design; and Figure 2 is a right side elevational view thereof.

I claim:

The ornamental design for a support for coat hangers, as shown.
